SEVERING MECHANISM

**Gay Monroe Bonebrake, Chicago, Ill., assignor to
Wm. Wrigley, Jr. Company, Chicago, Ill., a cor-
poration of Delaware**

Application July 5, 1949, Serial No. 102,986

14 Claims. (Cl. 107—7)

1

This invention relates to a severing mechanism, and more particularly to the parts, ensemble and relationships of structure embodied in a mechanism suited to use in the severance of individual pieces of like size from a stack of scored sheets or slabs of the material.

One of the objects of my invention is to provide a severing mechanism of the type referred to and which embodies two feeding mechanisms driven at related speeds; one of which feeding mechanisms effects an initial movement of a scored sheet from a stack, and the other of which takes over the feeding of the scored sheet after such initial movement and carries it on to a breaking mechanism.

Another object of my invention is to provide a severing mechanism of the class referred to and in which the scored sheets are successively fed from the bottom of a stack.

My invention has for a further object the provision of a severing mechanism adapted to high speed operation and suited to sudden stopping and starting as effected by an output control.

As another object, the invention comprehends the provision of a hopper-type retainer for stacked sheets or slabs and which has shiftable elements operated in timed sequence to the feeding of the sheets or slabs from the bottom thereof and in a sequence such that single sheets or slabs are released, while the rest of the stack is supported.

It is a further object of this invention to provide a severing mechanism incorporating a unified drive operating through a quick acting clutch which acts positively for starting and stopping the parts simultaneously and in unison; the speeds of the various parts being calculated normally to maintain a level of severed pieces between predetermined limits in an output hopper or stack as determined by a control element which effects operation of the clutch.

It is also within the purview of the design of each of the various parts of my severing mechanism to provide consistent high speed operation without damage to the material being severed and without the necessity of frequent manual adjustments or personal attention, other than that required to keep the mechanism supplied with material.

Other objects and advantages of the invention will be apparent from the following description and the accompanying drawings in which similar characters of reference indicate similar parts throughout the several views.

In the six sheets of drawings:

2

Figs. 1 and 2 are respectively front and rear elevational views of a mechanism embodying a preferred form of my invention;

Fig. 3 is an end elevational view, with portions broken away, of the mechanism depicted in Figs. 1 and 2;

Fig. 4 is a fragmentary front sectional view of a portion of the mechanism shown in Fig. 3, and wherein the section is taken substantially as indicated by a line 4—4 in Fig. 3 and accompanying arrows;

Fig. 5 is a fragmentary front sectional view, drawn to an enlarged scale, and wherein the section is taken on a line 5—5 of Fig. 3 and in the direction indicated by accompanying arrows;

Fig. 6 is a fragmentary end sectional view wherein the section is taken substantially on a line 6—6 of Fig. 5 and in the direction indicated by accompanying arrows;

Figs. 7 and 8 are fragmentary top sectional views taken substantially on lines 7—7 and 8—8 of Fig. 6, respectively, and in the directions indicated by the arrows;

Figs. 9, 10 and 11 are fragmentary diagrammatic views taken from the front of the illustrated mechanism and showing various sequential stages in the operation of portions of the illustrated mechanism;

Fig. 12 is a perspective view depicting a scored slab of material adapted to be severed into pieces by the indicated mechanism; and

Fig. 13 is a diagrammatic view of a portion of the mechanism, as depicted in Fig. 11, drawn to a larger scale.

In its more general aspects, the exemplary embodiment of my severing mechanism which is disclosed herein for illustrative purposes includes a hopper 15 having a top opening 16 through which stacked and scored slabs or sheets 17 are inserted into the interior thereof, and through which hopper those slabs or sheets gravitate while being maintained in an orderly stack. From the hopper 15, the scored slabs are fed individually and successively onto a chain-type conveyor mechanism 18 (Figs. 5, 6 and 8), which conveyor mechanism includes pusher block 19a, 19b, 20a, 20b, 22a and 22b in spaced relationship to one another for engaging end surfaces of individual slabs or sheets, as depicted in Figs. 9, 10 and 11, to push those slabs or sheets into engagement with feed rollers 23 and 24. The feed rollers 23 and 24 preferably have finely knurled surfaces and are supported for rotation with their axes parallel and spaced apart a distance

40 such that a slab or sheet, when fed thereto by

the conveyor mechanism, is gripped between the rollers and driven thereby.

In the disclosed structure, the surface speed of the feed rollers is somewhat faster than the speed of the pusher blocks, so that the feed rollers gradually move the sheet or slab away from its pusher block during the progress of the movement of the sheet or slab after the feed rollers have gripped it. Severing rollers 25 and 26 have parallel axes and are mounted for rotation with their axes substantially parallel to the axes of the feed rollers. Also, the severing rollers are spaced from the feed rollers a distance related to the length of the pieces 27 which are to be severed, and such that a scored line 28 is between the feed and severing rollers when the adjacent pieces are gripped by those rollers. The severing rollers are driven at a speed substantially greater than the speed of the feed rollers, whereby severance of adjacent pieces on a scored line is effected when those adjacent pieces are gripped by the two pairs of rollers. From the feed rollers, the pieces are fed into a hopper 29. In the disclosed structure, the conveyor mechanism, feed rollers and severing rollers are driven from a single prime mover (not shown) through a clutch 30 and drive shaft 32; the clutch being controlled by means, such as a photoelectric unit 33 through a solenoid 34, so as to maintain the level of pieces in the hopper 29 between preselected limits.

Although the material which is handled and severed by the mechanism might be varied and the sizes of the pieces changed, the disclosed mechanism is well suited for, and is illustrated in its application to the breaking of scored slabs of chewing gum into sticks. Each slab 17, in the present instance, comprises eight sticks linearly disposed in side-by-side relationship.

The disclosed hopper 15 is open at the front, as shown in Fig. 1, and has a back plate presenting a smooth inner surface. At the back, as shown in Fig. 2, the hopper is supported by a plate 36 through straps 37 and 38 secured to that plate and extending upwardly therefrom. A cross strap 39 is secured to the exterior surface of the back plate 35 to reinforce the hopper structure near the top. At the top, upwardly diverging side walls 40 and 42 extend forwardly from a top extension 43 on the back plate 35 and are braced by angle strips 44 and 45.

Rather than being completely closed, the opposite sides of the hopper 15 are defined by spaced guide strips disposed in aligned relationship with opposed edges facing inwardly of the hopper. As shown in Fig. 6, three guide strips 46, 47 and 48 are at one side of the hopper and are secured to the strap 38 by fastening means, such as bolts 49 and 50; the guide strips 46 and 47 being held in spaced relationship by spacing collars 52 and 53, the guide strips 47 and 48 being held in spaced relationship by spacing collars 54 and 55, and the guide strip 46, as well as the back plate 35 being spaced from the strap 38 by spacing collars 56 and 57. As shown in Fig. 3, the other side of the hopper includes guide strips 58, 59 and 60 in opposed relationship to the guide strips 46, 47 and 48 respectively and secured to the strap 37, by fastening means such as bolts 62 and 63. In this instance, the guide strips 58 and 59 are held in spaced relationship by spacing collars 64 and 65, the guide strips 59 and 60 are held in spaced relationship by spacing collars 66 and 67, and the guide strip 58, as well as the back plate 35 are spaced from the strap 37 by collars 68 and 69. For retaining the slabs at

the front of the hopper and as shown in Figs. 1, 3 and 6, retaining strips 70 and 72 are secured adjacent the guide strips 48 and 69 and have marginal portions which extend inwardly beyond those guide strips, so as to overlap opposite end portions of the slabs or sheets 17.

From the foregoing description of the hopper structure, it may be readily understood that a stack of slabs or sheets may be manually guided into the hopper between the side walls 40 and 42 and moved downwardly between the opposed guide strips 46, 47, 48, 58, 59 and 60 at the opposite sides of the hopper; the guide strips being spaced so that the slabs gravitate freely therebetween. For retaining and effecting the selective release of slabs at the lower end of the hopper, I have provided opposed gripping fingers 13, 14, 15 and 16 which are disposed between guide strips 46, 47, 48, 58, 59 and 60 and movably supported at their upper ends by being secured to shafts 71 and 78, which shafts are journaled in the straps 37 and 38 and guide strips 48 and 69, as illustrated in Figs. 3 and 6. As shown in Fig. 5, the gripping fingers utilized in the disclosed structure have lower end portions presenting opposed surfaces 79 and 80 which are disposed in obtuse angular relationship with respect to the opposed inner faces of the upper portions of those fingers; the opposed faces of the upper portions being substantially in planes corresponding to the inner edges of the guide strips. The surfaces 79 and 80 of the end portions being offset in the same direction, the lower slabs of the stack in the hopper are offset relative to one another. Also, the gripping fingers being movable about the axes of the shafts 71 and 78, those fingers may be caused to grip and to support opposite ends of the slabs 17, as well as to effect selective and timed release of the ends of the slab.

As shown in Figs. 5, 6, 7 and 8, the chain-type conveyor mechanism 18 is beneath and extends across the lower end of the hopper 15 immediately below the lower ends of the gripping fingers. This chain-type conveyor mechanism, in the disclosed structure, has two side chains 82 and 83 of similar structure and length supported in parallel relationship by stationary plates 84 and 85, which plates are convexly semi-circular at adjacent ends and have substantially straight and parallel edges lying in common planes which extend away from the semi-circular ends. At their opposite ends, the stationary plates 84 and 85 are concavely curved and sprockets such as 86 are secured to a shaft 87 and aligned in substantially coplanar relationship with the respective plates. Thus, the plates provide inner tracks around which the chains travel when driven by their respective sprockets.

Between the side chains 82 and 83, an intermediate chain 88 is supported by a plate 89, both ends of which are convexly semi-circular, so that the chain slides around the periphery thereof; the intermediate plate providing a path like that of the side chains for the intermediate chain but displaced from the side chains in a direction longitudinally to the bottom of the hopper. This offset relationship of the chains at their opposite ends causes the pusher blocks 19a, 19b, 20a, 20b, 22a and 22b to maintain substantially a predetermined level throughout their circuits of travel with the chains. These pusher blocks are connected to the chains at their opposite ends and present substantially vertical front pushing surfaces; each of the opposite ends thereof being connected to one of the chains, as shown in Fig.

8. Since the pusher blocks are mounted in pairs between the intermediate chain and the side chains, and each of the pairs is similarly connected to the chains with the pusher blocks in laterally aligned relationship, a description of the mounting of one pair will suffice for all. As illustrated in Fig. 8, a pin 93 is secured to and projects from one end of the block 19a through the chain 83; the pin being rotatable relative to the chain. In like manner, a pin 94 is secured to and extends from the pusher block 19b through the chain 82. At the other ends of those pusher blocks, a pin 95 is secured to both of the pusher blocks 19a and 19b, and extends through the intermediate chain 83. Thus, the pusher blocks travel in adjacent pairs, and since the offset relationship of the side chains with respect to the intermediate chain is related to and determined by the distance between the pins at the opposite ends of the pusher blocks, those pusher blocks are maintained in level relationship throughout their travel. It may be readily observed that the intermediate chain is driven from the side chains through the pusher blocks and their respective pins, so that the intermediate chain remains in its proper aligned relationship to the side chains.

Between the chains 82, 83 and 88 and the lower ends of the hopper, and in the planes of the stationary plates 84, 85 and 89, guide bars 96, 97 and 98 are mounted; those guide bars being of greater height near their ends and being supported like the stationary plates 84, 85 and 89 between the side plate 36 and a side plate 100 by bolts such as 102. Spaced relationship is maintained between the side plates 36 and 100 and between those side plates and stationary plates 84, 85 and 89, as well as between the respective stationary plates by spacers such as 103, 104, 105 and 106 on the bolts such as 102. The guide bars 96, 97 and 98 have substantially straight top edges disposed in coplanar relationship which serve as rails along which the lowermost slab 17 is slid from the hopper. The pusher blocks, in each instance, extend above the top edges of the guide bars sufficiently to overlie the end of one slab, but not far enough to engage the slab above the lowermost one. The spacing of the pusher blocks is sufficient that one slab 17 has room for some movement longitudinally of the guide bars between the projecting portions of those pusher blocks.

The feed rollers 23 and 24 are secured to shafts 107 and 108 respectively, which shafts are journalled at their opposite ends in the plates 36 and 100. As shown in Figs. 2 and 3, a sprocket 109, external to the plate 36 and secured to the shaft 108 has a driving connection to the shaft 87 through a drive chain 110 and a sprocket 112 which is secured to the shaft 87. Also external to the plate 36, a gear 113 is drivingly secured to the shaft 108 and meshes with a gear 114 on a stud shaft 115 which is secured to and projects from the side plate 36. Another gear 116 is rotatably mounted on a stud shaft 117 which is secured to and projects from the plate 36, and meshes with the gear 114, as well as a gear 118 which is secured to the shaft 107 of the feed roller 23.

With this drive arrangement, the feed rollers are both driven in directions such that they move the slabs away from the conveyor mechanism and in the same direction as they are moved by the pusher blocks of that conveyor mechanism. In the disclosed structure, however, the gear ratios for driving the feed rollers are such

that they move a slab of gum a little faster than it is moved by the pusher blocks of the conveyor mechanism, whereby a slab which has been engaged by the feed rollers is gradually drawn away from the pusher block which moved it into engagement with the feed rollers. This relationship of speeds has a tendency to avoid difficulties due to the jamming of a slab between the pusher blocks and the feed rollers. In order to effect the movement of a slab by the feed rollers when the slab is engaged by those rollers, they are spaced to firmly grip the slab therebetween and preferably have spiral knurling on the outer surfaces thereof. In the disclosed structure, the feed rollers 23 and 24 have grooves 119 and 120 therein, which grooves accommodate the stationary plates 84, 85, and 89 as well as the guide bars 96, 97 and 98.

As depicted in Fig. 1, a gear 122 is secured to the end of the feed roller shaft 108 outside of the plate 100 and drives the severing roller 26 through a gear 123 and a gear 124; the gear 123 being rotatably carried by a stud shaft 125 which is secured to and projects outwardly from the plate 100, and the gear 124 being secured to the end of a shaft 126, which latter shaft is the shaft of the severing roller 26. The adjacent severing roller has a shaft 127 and is driven from the shaft 126 by gears 128 and 129 which are secured to adjacent ends of those shafts, as shown in Fig. 2.

The surfaces of the severing rollers, like those of the feed rollers, have spiral knurling thereon and are spaced so as firmly to grip the end piece of a slab when it is fed thereto. The spacing of the severing rollers from the feed rollers is related to the size of the pieces which are to be severed so that adjacent pieces are gripped by the feed and severing rollers when a scored line on the slab is intermediate those sets of rollers. Also, the speed of the severing rollers, which is established by the driving gears, is materially faster than the speed of the feed rollers, whereby the end piece of the slab is drawn away from the adjacent piece and severed therefrom upon being gripped by the severing rollers.

As in the instance of the feed rollers, the severing rollers 25 and 26 have axially spaced peripheral grooves 130 and 132 therein which are aligned with the stationary plates 84, 85 and 89. These grooves, in this instance, however, not only accommodate those stationary plates which are so shaped as to provide downwardly and outwardly projecting fingers 133 adjacent the lower severing roller, but also accommodate movably deflecting fingers 134 adjacent the upper severing roller. The deflecting fingers, as shown in Figs. 3 and 5, are secured to a shaft 135, which shaft is journalled in bearings at the tops of the plates 36 and 100 and are biased downwardly toward the grooves of the severing roller by springs 136. At their outer ends, the fingers 134 have projecting curved portions 137 which normally extend downwardly into the path of the pieces as they are ejected from the severing rollers, so that the fingers are deflected upwardly against the spring force by each piece, and each piece is deflected downwardly into the hopper 29.

The hopper 29, as shown in Figs. 1, 2 and 3, is supported by the plates 36 and 100 through side brackets 138 and 139 which are secured to those plates. Preferably, the hopper has studs 140 and 142 projecting outwardly therefrom in aligned relationship and journalled in the side brackets so that the hopper is swingable from its normal vertical position, as shown in Fig. 2.

At the top, the hopper 29 and plates 36 and 100 respectively have aligned apertures 143 and 144 therein, through which a beam of light is projected to the photoelectric unit 33. Thus, the height of the stack of pieces in the hopper 29, when it rises above a predetermined level, interrupts the light beam to stop the breaker mechanism until the level of that stack again drops below a predetermined limit, at which the light beam is again projected to the photoelectric unit.

For driving the mechanism, including the conveyor mechanism, the feed rollers, the severing rollers and the movable fingers, I have provided flexible joints 145 and 146 in the drive shaft 32 which extends from the clutch 39 to the shaft 108. This avoids any difficulty due to the slight misalignment of the parts. The clutch 39 through which the mechanism is driven, is preferably of a quick acting and relatively positive overrunning type and has a coil spring 147 biasing the clutched parts to their driving positions; the spring extending around a hub 148 secured to the shaft 32 and having one end anchored to a clutch housing plate 149 and its other end anchored to the hub.

A plurality of studs 150 project outwardly in a direction parallel to the shaft 32 from the clutch housing plate 149 and are disposed at equally spaced positions around the axis of the shaft 32. A latch detent 152 is supported for swinging movement about a shaft 153 and has a notched end portion 154 which normally tends to gravitate to a position of abutment with one of the studs 150. The movable end of the latch detent is connected to an armature 155 of the solenoid 34 through a link 156. Driving force for the mechanism is supplied through the clutch from a convenient source such as an electric motor (not shown). When the solenoid is energized as a result of the level of the pieces of gum in the hopper 29 being below the light apertures, the driving force is transmitted to the breaking mechanism from the source. On the other hand, when the stack in the hopper 29 extends above the predetermined level, the solenoid is deenergized and the latch detent 152 falls to a position of abutment with one of the projecting studs 150. This interrupts the supply of driving power to the breaking mechanism, and effects a stoppage thereof for a short interval of time until the level in the hopper 29 falls. It is particularly desirable that the action of the clutch shall be quick and positive, so that the breaking mechanism is started and stopped definitely, rather than merely changing speed or lagging in its operation, as the result of sluggish clutch response.

For actuating the fingers 73, 74, 75 and 76 at the opposite sides of the main hopper 15 in the manner to effect the release of the bottom slabs from that hopper sequentially and in timed relationship to the movements of the conveyor mechanism 18, I have provided a cam 157 (Fig. 2) on the shaft 87, external to the plate 36. This cam coacts with a following roller, 158 carried by a linkage which includes lever arms 159 and 160 secured at their upper ends to the shafts 77 and 78 which carry the fingers 73, 74, 75 and 76, and are connected at their lower ends by a cross link 162 upon which the roller 158 is mounted. A tension spring 163 has one end connected to the lever arm 159 and its other end anchored to the plate 36 at positions such that it biases the roller 158 into engagement with the cam 157. It is to be noted that in the disclosed structure the angular positions of the lever arms 159 and 160 are 75 feed rollers located just beyond said one end of

different with respect to the positions of the fingers 73, 74, 75 and 76, so that the angular movements of the lever arms which is effected by the cam causes different amounts of angular movement of the fingers at different parts of their movement cycles.

As shown in Figs. 5 and 7, the relative angular positions between the lever arms 159 and 160 and the fingers which are connected thereto are adjustable by set screws 164 and 165. The lever arms 159 and 160 respectively have cross arms 166 and 167 projecting therefrom in directions lateral to the sides of the hopper. The set screws are located relative to those cross arms by means such as nuts 168 and 169 on opposite sides of the cross arms and are threaded into cross pins 170 and 172 on the respective fingers.

Figs. 9, 10, 11 and 13 are provided to illustrate various sequential steps in the operation of the feeding and severing mechanism, including the timing of the movements of the various parts. As shown in Fig. 9, the pusher block 20a has just engaged the end of a slab at the bottom of the hopper 15; the preceding slab having passed from the conveyor mechanism to the control of the feed rollers 23 and 24. As the lowermost slab is moved along and into the feed rollers 23 and 24, the fingers 74 and 76 swing to the right as viewed in Fig. 10 with the finger 74 having somewhat greater angular movement than the finger 76, so that the ends of the slab adjacent the finger 74 are released, allowing the one end of the next slab to drop down to the surfaces of the guide bars 96, 97 and 98. During continued movement of the lowermost slab, the fingers 74 and 76 move back to the left in timed relationship to the progress of the slab, and so as to move the finger 76 away from the adjacent ends of the slabs, as shown in Fig. 13, just as the preceding slab reaches those ends of the slabs above, whereby the forward ends of the upper slabs drop down as soon as the preceding slab is out of the way. At this point, the sequence proceeds from the position depicted in Fig. 9. It may be observed that the lowermost slab moves away from the pusher block after the feed rolls have gripped it. It may also be observed that the upper slabs of the stack are supported in their respective positions until released during the reciprocating movements of the fingers 73, 74, 75 and 76.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A mechanism for severing scored sheets or slabs of material into pieces of predetermined size and comprising, in combination, a hopper 65 having a top opening for receiving a stack of scored sheet material, said hopper being of a size and disposition such that said material is normally maintained in an orderly stack and tends to gravitate therethrough, means for releasing one sheet of material at a time from the bottom of the hopper, a chain-type feeding mechanism for receiving the sheets of material from the hopper, said mechanism having one end just beyond one end of the hopper, a pair of 70 feed rollers located just beyond said one end of

the chain-type feeding mechanism for receiving and gripping each sheet of material from the chain-type feeding mechanism, a second pair of rollers on the opposite side of the feed rollers from the chain-type feeding mechanism and disposed in predetermined spaced relationship to the feed rollers to grip the sheet material as it is fed thereto by the latter mentioned rollers, and a driving mechanism for driving the chain-type feeding mechanism, said feed rollers and the second pair of rollers at different and related surface speeds, said feed rollers having a surface speed somewhat greater than that of the chain-type feeding mechanism so as to effect movement of each gripped sheet of material relative to the chain-type feeding mechanism in the direction of travel of the sheet, the surface speed of the second pair of rollers being materially faster than that of the feed rollers so that the material is severed into pieces between the pairs of rollers.

2. In a mechanism for severing scored sheets or slabs of material into pieces of predetermined size, the combination comprising a chain-type feeding mechanism for receiving the sheets of material and having pushing elements projecting laterally therefrom in spaced relationship to one another for insuring movement of the sheets, a pair of feed rollers adjacent one end of the chain-type feeding mechanism for receiving and gripping each sheet of material from the chain-type feeding mechanism, a second pair of rollers on the opposite side of the feed rollers from the chain-type feeding mechanism and disposed in predetermined spaced relationship to the feed rollers to grip the sheet material as it is fed thereto by the latter mentioned rollers, a driving mechanism for driving the chain-type feeding mechanism, the feed rollers and the second pair of rollers at different and related surface speeds, the surface speed of the feed rollers being greater than the linear speed of the chain-type feeding mechanism so that material gripped by the feed rollers is moved away from the projecting pushing elements, and the speed of the second pair of rollers being materially faster than that of the feed rollers so that the material is severed into pieces between the pairs of rollers.

3. In a mechanism for severing scored sheets or slabs as defined in claim 2, said driving mechanism including a clutch, and means for effecting substantially instantaneous action of the clutch for regulating the output of said second pair of rollers.

4. In a mechanism for severing scored sheets or slabs of material into pieces, the combination comprising stationary retaining members in spaced and opposed relationship for receiving a stack of slabs therebetween, end retaining members for the slabs hingedly connected at their upper ends to the stationary members for swinging movements in directions parallel to the planes of the stationary members, said end retaining members having lower end portions presenting opposed surfaces angularly offset in one direction in the plane of said movements, so that the lower sheets of the stack are successively offset from one another, and means for controlling the positions of the end retaining members so that they normally grip the lower sheets of the stack therebetween and successively release the gripped ends of the bottom sheet of the stack by successive movements of the end retaining members away from the ends of said sheets.

5. In a mechanism for severing scored sheets or slabs of material into pieces, as defined in claim 4, said means for controlling the positions of the end retaining members including a linkage connecting the end retaining members, and cam means for actuating the linkage.

6. In a mechanism for severing scored sheets or slabs of material into pieces as defined in claim 5, the combination being further characterized by means for adjusting the positions of the end retaining members relative to said linkage.

15 7. In a mechanism for severing scored sheets or slabs of material into pieces, the combination comprising first and second pairs of material gripping rollers disposed in parallel relationship and separated a distance related to the size of the pieces being severed, means for driving both pairs of rollers with the second pair of rollers being driven faster than the first pair, one of the rollers of the second pair having a peripheral groove therein, a deflecting finger fitting into said groove and mounted for swinging movement toward and from the groove, said finger extending outwardly in a direction away from the first pair of rollers, and a spring biasing the finger toward said one of the rollers of the second pair.

8. A mechanism for severing scored sheets or slabs of material into pieces of predetermined size and comprising, in combination, a hopper having a top opening for receiving a stack of scored sheet material, said hopper being of a size and disposition such that said material is normally maintained in an orderly stack and tends to gravitate therethrough, means for releasing one sheet of material at a time from the bottom of the hopper, a chain-type feeding mechanism directly below the hopper for receiving the sheets of material from the hopper, said chain-type feeding mechanism being in the form of a loop one end of which is located just beyond one end of the hopper, a pair of feed rollers located just beyond said one end of the loop for receiving and gripping each sheet of material from the chain-type feeding mechanism, a second pair of rollers on the opposite side of the feed rollers from the chain-type feeding mechanism and disposed in predetermined spaced relationship to the feed rollers to grip the sheet material as it is fed thereto by the latter mentioned rollers, and a driving mechanism, said feed rollers and the second pair of rollers at related speeds, the speed of the second pair of rollers being materially faster than that of the feed rollers so that the material is severed into pieces between the pair of rollers, said means for releasing one sheet of material at a time from the bottom of the hopper including end wall members suspended for swinging movement relative to the rest of the hopper, said end wall members having corresponding and opposed inner end surface portions disposed in obtuse angular relationship to the upper portions thereof, so that the sheets at the lower portion of the stack are obliquely staggered, and means actuated by said driving mechanism for moving the end wall members alternately from side to side so as to release one end of one sheet at a time in timed relationship to the movements of the chain-type feeding mechanism.

70 9. A mechanism for severing scored sheets or slabs of material into pieces of predetermined size and comprising, in combination, a hopper having a top opening for receiving a stack of scored sheet material, said hopper being of a

11

size and disposition such that said material is normally maintained in an orderly stack and tends to gravitate therethrough, means for releasing one sheet of material at a time from the bottom of the hopper, a chain-type feeding mechanism for receiving the sheets of material from the hopper, a pair of feed rollers adjacent one end of the hopper for receiving and gripping each sheet of material from the chain-type feeding mechanism, a second pair of rollers on the opposite side of the feed rollers from the chain-type feeding mechanism and disposed in predetermined spaced relationship to the feed rollers to grip the sheet material as it is fed thereto by the latter mentioned rollers, and a driving mechanism for driving the chain-type feeding mechanism, said feed rollers and the second pair of rollers at related speeds, the speed of the second pair of rollers being materially faster than that of the feed rollers so that the material is severed into pieces between the pairs of rollers, said chain-type feeding mechanism including chain loops overlapping and displaced from one another in the direction of travel and being supported by stationary plates and driven by sprockets, said chain loops having parallel portions extending beneath the hopper and ends beneath and directly beyond said one end of the hopper adjacent the feed rollers, pusher blocks carried in spaced relationship between the chains and having each of their opposite ends pivotally connected to one of the chains, and said chains being so relatively disposed that the pusher blocks retain level positions throughout their paths of movement.

10. A mechanism for severing scored sheets or slabs of material into pieces of predetermined size and comprising, in combination, a hopper having a top opening for receiving a stack of scored sheet material, said hopper being of a size and disposition such that said material is normally maintained in an orderly stack and tends to gravitate therethrough, means for releasing one sheet of material at a time from the bottom of the hopper, a chain-type feeding mechanism for receiving the sheets of material from the hopper, a pair of feed rollers adjacent one end of the hopper for receiving and gripping each sheet of material from the chain-type feeding mechanism, a second pair of rollers on the opposite side of the feed rollers from the chain-type feeding mechanism and disposed in predetermined spaced relationship to the feed rollers to grip the sheet material as it is fed thereto by the latter mentioned rollers, and a driving mechanism for driving the chain-type feeding mechanism, said feed rollers and the second pair of rollers at related speeds, the speed of the second pair of rollers being materially faster than that of the feed rollers so that the material is severed into pieces between the pairs of rollers, said chain-type feeding mechanism including parallel traveling chain loops displaced from one another in the direction of travel and extending beneath the hopper, said chain loops having ends beneath and directly beyond said one end of the hopper adjacent the feed rollers, said chain loops having pusher blocks connected thereto and presenting end faces projecting outwardly of the chain at positions separated a distance greater than the length of a sheet.

11. A mechanism for severing scored sheets or slabs of material into pieces of predetermined size and comprising, in combination, a hopper

12

having a top opening for receiving a stack of scored sheet material, said hopper being of a size and disposition such that said material is normally maintained in an orderly stack and tends to gravitate therethrough, means for releasing one sheet of material at a time from the bottom of the hopper, a chain-type feeding mechanism for receiving the sheets of material from the hopper, said mechanism having one end just beyond one end of the hopper, a pair of feed rollers located just beyond said one end of the chain-type feeding mechanism for receiving and gripping each sheet of material from the chain-type feeding mechanism, a second pair of rollers on the opposite side of the feed rollers from the chain-type feeding mechanism and disposed in predetermined spaced relationship to the feed rollers to grip the sheet material as it is fed thereto by the latter mentioned rollers, and a driving mechanism for driving the chain-type feeding mechanism, said feed rollers and the second pair of rollers at related speeds, the speed of the second pair of rollers being materially faster than that of the feed rollers so that the material is severed into pieces between the pairs of rollers, said driving mechanism including a clutch for controlling the driving connection to both pairs of rollers and the chain-type feeding mechanism, and means responsive to the output of pieces from the second pair of rollers for effecting engagement and disengagement of the clutch.

12. A mechanism for severing scored sheets or slabs of material into pieces of predetermined size and comprising, in combination, a hopper having a top opening for receiving a stack of scored sheet material; said hopper being of a size and disposition such that said material is normally maintained in an orderly stack and tends to gravitate therethrough, means for releasing one sheet of material at a time from the bottom of the hopper, a chain-type feeding mechanism below the hopper for receiving the sheets of material from the hopper, said mechanism having one end adjacent one end of the hopper, a pair of feed rollers adjacent said one end of the hopper for receiving and gripping each sheet of material while being delivered from said one end of the feeding mechanism, a second pair of rollers on the opposite side of the feed rollers from the chain-type feeding mechanism and disposed in predetermined spaced relationship to the feed rollers to grip the sheet material as it is fed thereto by the latter mentioned rollers, and a driving mechanism for driving the chain-type feeding mechanism, said feed rollers and the second pair of rollers at related speeds, the speed of the second pair of rollers being materially faster than that of the feed rollers so that the material is severed into pieces between the pairs of rollers, the chain-type feeding conveyor including elements for pushing each sheet from the bottom of the hopper, and the surface speed of said feed rollers slightly exceeding the speed of movement of said elements, so that the sheets are drawn away from the elements when moved by the feed rollers.

13. A mechanism for severing scored sheets or slabs of material into pieces of predetermined size and comprising, in combination, a hopper having a top opening for receiving a stack of scored sheet material; said hopper being of a size and disposition such that said material is normally maintained in an orderly stack and tends to gravitate therethrough, means for releasing

one sheet of material at a time from the bottom of the hopper, a chain-type feeding mechanism for receiving the sheets of material from the hopper, said mechanism having one end just beyond one end of the hopper, a pair of feed rollers located just beyond said one end of the chain-type feeding mechanism for receiving and gripping each sheet of material from the chain-type feeding mechanism, a second pair of rollers on the opposite side of the feed rollers from the chain-type feeding mechanism and disposed in predetermined spaced relationship to the feed rollers to grip the sheet material as it is fed thereto by the latter mentioned rollers, a driving mechanism for driving the chain-type feeding mechanism, said feed rollers and the second pair of rollers at related speeds, the speed of the second pair of rollers being materially faster than that of the feed rollers so that the material is severed into pieces between the pairs of rollers, and spring biased fingers adjacent the second pair of rollers for deflecting the pieces downwardly as those pieces leave the second pair of rollers.

14. In a mechanism for severing scored sheets or slabs of material into pieces, the combination comprising a hopper having a top opening for receiving a stack of scored sheet material, said hopper being of a size and disposition such that said material is normally maintained in an orderly stack and tends to gravitate therethrough, means for releasing one sheet of ma-
